ATTORNEY

UNITED STATES PATENT OFFICE.

NUMA J. BOURGE, OF ERATH, LOUISIANA.

RAILWAY-SIGNAL.

1,348,080.

Specification of Letters Patent. Patented July 27, 1920.

Application filed November 27, 1916. Serial No. 133,724.

To all whom it may concern:

Be it known that I, NUMA J. BOURGE, a citizen of the United States, residing at Erath, in the county of Vermilion and State of Louisiana, have invented certain new and useful Improvements in Railway-Signals, of which the following is a specification.

The present invention has reference, generally, to improvements in signals; and the invention relates, more particularly, to a novel railway signal.

The invention has for its principal object to provide a signal, whereby the approach 15 of a train will be announced, previous to its passing a cross-road, thereby warning pedestrians and drivers of vehicles and preventing collisions and other forms of accidents.

As an object of equal importance, the invention aims to provide a signal which will be both visual and audible, thus preventing misinterpretation of the warning signal.

Among other aims and objects of the invention may be recited, the provision of a signal of the character mentioned with a view to compactness, and in which the number of parts are few, the construction simple, the cost of production small, and 30 efficiency of operation high.

Other and further improvements and novel details in the construction and arrangement of parts will be appreciated from the description to follow, which for a clear 35 understanding of the invention should be considered in connection with the accompanying drawings forming a part thereof and wherein a preferred embodiment of the invention is shown for the purpose of illustration.

In the drawings:

Figure 1 is a fragmental side elevation of a railway track with my improved signal arranged thereon,

Fig. 2 is a top plan of the same;

Fig. 3 is a fragmental detail in side elevation showing the connection of the signal operating means with the tripping means, and

Fig. 4 is a fragmental detail in top plan of one of the trip members.

Fig. 5 is a longitudinal section view through one end of one of the ties, illustrating the manner in which the spring normally retains the head in position beside the rail to facilitate its depression.

Fig. 6 is a detail perspective view of a depressor head and the support thereof used in the present device.

Referring now more particularly to the drawings, wherein like reference characters designate corresponding parts throughout the several views thereof, I have shown by way of illustration the present improvements as applied to an ordinary railway 60 track, the rails of which are indicated by the numeral 1 and the cross ties by the numeral 2, certain of which, are of greater width than others, the purpose of which will be subsequently apparent.

Referring to the present improvements, a supporting standard 3 is arranged in proximity of one of the rails 1, the lower end thereof being suitably embedded within a foundation, which may be and preferably 70 is formed of cement or the like, whereby the said standard will be rigidly held in position. A signal 4, in the shape of an arrow, is pivotally supported within the bifurcated upper extremity of the supporting standard 3, as at 5, and serves as the visual indicating means. A bell or other similar form of audible signal 6 is connected to the rear end of the arrow 4, by means of a link 7 and when shifted from 75 one position to another by the movement of the arrow 4, will, of course, ring, thus affording the audible signal. A weight 8 is affixed to the rear extremity of the arrow 4 and, obviously, maintains the same 80 normally in inoperative position.

With a view toward providing means whereby the arrow 4 and bell 6 will be actuated, there is formed within the wider of the cross ties 2, recesses 9 which have 85 arranged therein the lateral offset bearing portions of substantially bell cranked shape arms 10, the said lateral portions being indicated by the numeral 11. To secure the portions 11 within the recesses 9, staples or 90 like 12 are engaged thereover and driven into the ties upon which the arms 10 are arranged. Heads 13 are arranged upon the outer ends of the arms 10 and have formed thereupon, offset portions 13', 100 which portions are receivable within notches or recesses formed in the tread portion of the adjacent rail 1. To maintain the heads 13 in proper position with relation to the particular rail 1 as arranged adjacent thereto, a metal bracket or strap 15 is arranged about the side portions of each 105 110

- of the heads and, as will be noted, will prevent undue lateral movement thereof. By this arrangement, an efficient tripping means is provided. To normally maintain 5 the outer end of the arms 10 which carry the heads or trips 13, in their uppermost positions, the arm of a coiled spring 16 is engaged with the under faces of the heads; hence, it will be appreciated that the heads 10 or trips will be yieldably held in the desired position. To secure the springs 16 in position, pins 17 are passed therethrough and embedded within the side walls of recessed portions 18. A rod 19 is slidably 15 mounted upon the cross ties 2 and has upwardly bent portions 20 terminating in horizontally extending portions 20' whereby the upper ends of the arms 10 can be engaged with the horizontally extending 20 portion. To prevent the arms 10 from disengaging the horizontally bent portion of the rod 19, stop fingers 21 are formed upon the ends of portions 20. It is to be noted, that the rod 19 is moved in but a single 25 direction for operating the signal and, consequently, a pull must be delivered thereupon by one of the arms 10 when actuated, while a push must be delivered thereupon by the remaining arm when it is actuated. 30 To allow the last mentioned arm to shift the rod 19, a stop 22 is arranged upon one of the horizontally extending portions 20'. A rod 23 is connected with the forward end of the arrow 4, as at 24 and extends into 35 engagement with a bell crank lever 25, which is pivotally secured to one of the cross ties, as at 26, the connection between the lever and the rod being indicated by the numeral 27. The remaining end of the lever 25 is 40 received within a looped portion 28 formed in the sliding rod 19. Thus, movement of the said arm 19 will be transmitted to the bell crank arm and thence, through the medium of the rod 23 to the arrow 4. 45 The operation of the construction may be reviewed as follows:
- The offset portions 13' of the trips 13 are normally held, by means of the springs 16, in a position above the tread surface of the 50 rails 1. Consequently, when the wheels of the rolling stock engage the same, the arms 10 will be oscillated and a sliding movement imparted to the rod 19, which, by reason of its indirect connection with the arrow 4 will 55 cause that member to be moved into operative or signaling position. During movement of the arrow to signaling position, the audible signal 6 will be actuated. Hence, a dual signal will be afforded and 60 pedestrians and drivers of vehicles warned of the approach of the train. When the trips are disengaged from the wheels of the rolling stock, the weight 8 as arranged upon the rear portion of the arrow 4 will return 65 the said arrow to inoperative position, while

the arms of the springs 16 will return the offset portions 13' to their normal positions with relation to the rail 1 and the construction rendered ready for a second or further operation.

It will be noted that as the vertical arm of the lever 25 is swung in either direction it will describe an arc about the pivotal point of the lever. This movement is allowed by the shifting of the rod 19, since the horizontally extending portions and the upwardly bent portions of the rod 19 are carried by the arms 10. By referring to Fig. 1, it will be noted that the arms 10, when in normal position, extend to one side of planes extending perpendicularly from the ties and for this reason as these arms are swung in either direction, their outer ends will also describe the arc of a circle. Owing to their greater length, the arc thus described will 75 be greater than the arc described by the vertical arm of the lever 25 and as a result the rod 19 will be lifted from the ties 2 at times and then moved back toward the ties 2, as the arms 10 are swung. Therefore, the rod 19 will move to accommodate the arcuate movement of the vertical arm of the lever 25, thus permitting this lever to move to operate the pintle 4 through the rod 23.

It is to be understood, that the sliding rod 95 19 may be of any desired length and of course, the trips placed at a suitable distance from the cross-over, so as to give ample warning to persons, before the train passes the cross-over.

While I have illustrated and described with a considerable degree of particularity, constructional details of the device embodying my invention, it is to be understood that the invention is not limited to the particular 105 form and arrangement of the several parts, which may be modified within a wide range without departing from the essence of the invention the construction shown and the description based thereon being intended to 110 be taken in an illustrative, rather than a limiting sense.

I claim:

1. In a device of the class described, the combination of a signaling element, a longitudinally extending rod, means connecting said rod to said signaling element, thus permitting the signaling element to be operated when said rod is shifted, said rod having upwardly bent portions at its ends, said ends terminating in horizontally extended portions, and means connected to said horizontally extending portions for shifting said rod.

2. In a device of the class described, the combination of a standard, a signaling element pivotally mounted upon said standard, a bell-crank lever, a rod connected to said bell-crank lever and said signaling element, a second rod connected to said bell-crank 130

lever, means for shifting said second mentioned rod in one direction, thus causing the bell-crank lever to be moved to pull upon said first-mentioned rod and actuate said signaling element, and said signaling element being adapted to return said bell-crank lever and said last mentioned arm to their normal positions after said means has been released.

3. In a device of the class described, the combination of a longitudinally extending rod, said rod having upwardly bent portions terminating in horizontally bent portions, arms connected to said horizontally extending portions, said horizontally extending portions having lugs at their ends, one of said horizontally extending portions having a stop intermediate its ends, means for oscillating said arms, thus shifting said rod, a signaling element, and means connected to said rod and to said signaling element, thus causing the actuation of said signaling element as said rod is shifted.

4. In a device of the class described the combination of a supporting member, a signaling element pivotally mounted upon said member, a bell crank lever, a rod connected to said bell crank lever, and rod signaling element, a second rod connected to said bell

crank lever, said last mentioned rod having upwardly bent portions at its ends, said ends terminating in horizontally extended portions and means connected to said horizontally extended portions shifting said last mentioned rod.

5. In a device of the class described, the combination of a standard, a signaling element pivotally mounted upon said standard, a bell crank lever, a rod connected to said bell crank lever and said signaling element, a second rod connected to said bell crank lever, having upwardly bent portions terminating in horizontally bent portions, arms connected to said horizontally extending portions, said horizontally extending portions having lugs at their ends, one of said horizontally extending portions having a stop intermediate its ends, and means for oscillating said arms, thus causing said signaling element to be actuated.

In testimony whereof I affix my signature in presence of two witnesses.
